UNITED STATES PATENT OFFICE.

HENRY W. SAYLES, OF PEORIA, ILLINOIS, ASSIGNOR, BY MESNE ASSIGNMENTS, TO
GEORGE M. WILLIS, OF CHICAGO, ILLINOIS.

PREPAYMENT ARRANGEMENT FOR METERS.

No. 879,913.

Specification of Letters Patent.

Patented Feb. 25, 1908.

Application filed December 4, 1905. Serial No. 290,133.

To all whom it may concern:

Be it known that I, HENRY W. SAYLES, citizen of the United States, residing at Peoria, in the county of Peoria and State of Illinois, have invented a certain new and useful Improvement in Prepayment Arrangement for Meters, of which the following is a full, clear, concise, and exact description, reference being had to the accompanying drawings, forming a part of this specification.

My invention relates to electrical prepayment devices, and particularly to such devices adapted for association with electric meters, and its object is to provide a more simple and a more efficient device of this kind.

The device may be adapted for use with different kinds of meters and is provided with electromagnetic circuit controlling mechanism whose circuit is controlled by very simple contact mechanism which in turn is controlled by the coins or slugs passing through the device.

My invention will be better understood by reference to the accompanying drawings, in which

Figure 1 shows my device attached to a meter. Fig. 2 is a sectional view taken on line 2—2 of Fig. 1. Fig. 3 is a sectional view of contact mechanism employed. Fig. 4 is a sectional view taken on line 4—4 of Fig. 3, and Fig. 5 diagrammatically shows the electrical connection.

The mechanism is contained within a casing or box 1 through which a coin slot 2 extends from the top to the bottom to empty into a receptacle or drawer 3 at the lower end of the box. An opening or slot 4 leads through the inner edge of the coin slot or channel near the lower end thereof and projecting through said slot into the coin channel is a wheel 5 provided with the teeth or prongs 6. This wheel is secured to a bushing 7, and the hub 8 also secured to this bushing 45 has an arm 9 from which extends a contact pin 10. The bushing 7 is preferably of insulating material and provided with the flange 11 for insulating the wheel from the hub 8. This bushing is pivotally mounted on a shaft 12 bearing in the supports 13 and 14. On said shaft adjacent to the hub 8 is secured a second hub 15 from which extends an arm 16 having at its end the slot or groove 17 between the ends 18 and 19. The contact pin

10 plays in this slot 17 between the ends 18 and 19, but the end 18 has a lining 20 of insulating material so that the contact arm 10 can form electrical connection only with the end 19 which may be provided with a contact tip 21 of silver or other suitable material. Secured to the inner end of the shaft 12 is the bevel gear 22, and a bushing 23 of insulating material insulates the hub 15 from the shaft and from the support 14. A spring 24 secured at one end to the shaft 12 and at the other end to the arm 9 tends to hold the contact extension 10 in electrical engagement with the contact tip 21 on the end 19 of the arm 16.

Suitably journaled in the supports 25 and 26, or otherwise, is a spindle or shaft 27 having secured to its lower end a gear 28 to mesh with the gear 22 and near its upper end a bevel gear 29 to mesh with a bevel gear 30 secured to a shaft 31 extending to the exterior of the casing 1 for connection with the movable element of the meter. Carried on the supporting frame 32 is a solenoid 33 within which a core 34 may reciprocate. This core at its lower end is provided with a switch blade 35 insulated therefrom and adapted to electrically connect together the contact terminals 36 and 37. To insure better contact the switch blade may have the wedge extensions 38 and 39 for engaging respectively in the notches 40 and 41 in the contact terminals 36 and 37. The solenoid at its upper end may be provided with a stationary core section 42 whereby less current will be necessary to hold the movable core after attraction than to cause movement thereof, and the movable core may also be provided with guide rods 43 and 44 passing respectively through the core section 42 and a supporting frame 45, which also supports the contact terminals 36 and 37, but insulated therefrom as shown. Extending from the support 25, but insulated therefrom and from each other, are the brushes 46 and 47 engaging respectively the hubs 8 and 15 of the contact mechanism.

The wheel 5 is preferably formed by cutting segments therefrom having an arc equal to that of the coins for which the device is designed, and the teeth or prongs 6 extending into the coin channel 2 form also escape mechanism for the coins. As before stated, the tendency of the spring 24 is to hold the arms 9 and 16 in electrical engage-

ment, but the weight of a single coin is sufficient to rotate the wheel with respect to the shaft 12 to carry the contact extension 10 to the other end of the slot 17 and out of 5 electrical engagement with the end 19 of the arm 16. The solenoid and the brushes are suitably connected in circuit so that when there are no coins in the coin channel the contact 10 will be in engagement with the 10 arm 19 and circuit closed through the solenoid to carry the core and switch blade from the contacts terminals 36 and 37, these terminals being suitably connected with the meter circuits to prevent current flow 15 through the meter and to the main circuit controlled thereby. When a coin or coins, however, are in the channel the wheel will be rotated to break connection between the contacts 10 and 19 and the energizing circuit 20 for the solenoid will be broken and the core thereof will be moved to cause closure of the circuits controlled thereby, and upon connection of a translating device in circuit the meter will operate. The meter during 25 operation causes also rotation of the shaft 12 through the intervening gearing mechanism and shafting, and the wheel 5 is turned, the solenoid controlling circuit being held open during all the time that the coin is 30 exerting pressure on a wheel tooth, but the instant that the wheel releases the coin the spring 24 will return the wheel to carry the contacts 10 and 19 into engagement with each other thereby to again close the circuit 35 through the solenoid and to cut off the current supply to the main circuit. The rotation of the wheel, of course, is adjusted so that the proper amount of current will be delivered during the passage of each coin by 40 the escapement wheel, and if several coins are in the slot the operation of the meter will be continuous until the last coin has been released.

Fig. 5 diagrammatically shows the connection of my device with one form of meter. This meter comprises an armature 48 mounted on a spindle 49 pivoted in the bearings 50 and 51, a commutator 52 suitably connected with the armature winding being also 50 mounted on the spindle and engaged by the brushes 53 and 54. A damping disk 55 also mounted on the spindle is suitably controlled by a damping magnet 56. A worm thread 57 is provided at the upper end of the spindle 55 and engaged by the worm wheel 58 secured to the end of the shaft 31 extending from the prepayment mechanism. A field coil 59 surrounds the armature and upon current flow through both field coil and armature the 60 armature and spindle will rotate and the revolutions thereof will be suitably indicated on the indicating dial 60. As shown in Fig. 1, the casing 1 is adapted for separable attachment to the frame 61 of the meter, 65 being, therefore, provided with lugs 62

through which fastening screws 63 may pass into engagement with the meter frame, the shaft 31 passing through both frames. The circuit connections for the instrument are best shown in Fig. 5. A source of current 64 is adapted to provide current for translating devices T suitably connected with the line limbs *a* and *b*. The line limb *a* serially includes the field winding 59 and the switch terminals 36 and 37. The pressure circuit 70 of the meter extends from the line limb *a* through the commutator and armature to the line limb *b*. The controlling circuit extends from the line limb *a*, through the solenoid, brush 47, through the contact mechanism to the brush 46 and to the line limb *b*; and a resistance *r* may also be included in this circuit. When there is no coin in the meter, and consequently no pressure on the wheel 5, the controlling circuit 75 will be closed through the contact mechanism as before described, and the core 34 held in position to open the current circuit at the switch contacts 36 and 37. Immediately upon insertion of a coin, however, the wheel 80 and contact mechanism will be moved to open the controlling circuit whereby the core is released to connect together the contacts 36 and 37 to close the series circuit of the meter and to allow current flow to the translating devices, the meter at the same time beginning to operate. The movements of the meter armature are transmitted through the worm thread 57, worm wheel 58, shaft 31, gears 30 and 29, shaft 27, gears 28 and 22, shaft 12 and through the contact mechanism to the wheel 5, this gearing being 85 adjusted to cause rotation of the wheel dependent upon the energy to be delivered to the translating device in return for the coin or coins within the coin channel. Immediately after the last coin passes the wheel 90 5 the controlling circuit will be closed to open the current circuit and current flow to the translating devices prevented.

The coins after passage through the channel drop into the receptacle 3. To normally protect the mechanism and to allow access thereto for inspection or repairs a cover 65 may be hinged or otherwise supported on 95 the casing to be locked thereto, and this cover may also extend over the entrance to the receptacle 3. The front wall 66 of the coin channel may be of glass or other transparent material and the cover, if opaque, may be provided with an opening disposed before the glass wall of the channel so that the subscriber may at any time see the number of coins in the device. To prevent tampering the upper part 67 of the coin channel 100 may also be irregular or offset as shown.

The prepayment device herein described can be adapted for connection with different kinds of meters. The arrangement of the controlling parts in the device are very few 105

and very simple, there being no delicate mechanisms which could easily be deranged or rendered inaccurate.

Many changes may be made in the arrangement and construction of the various parts without departing from the spirit of my invention, and I do not, therefore, wish to be limited to the arrangement and construction herein shown.

Having described the above embodiment of my invention I claim as new and desire to secure by Letters Patent:

1. The combination with the movable element and pressure and current circuits in a meter, of prepayment mechanism for controlling said circuits, electromagnetic mechanism for the prepayment mechanism included in the pressure circuit for controlling the current circuit, contact mechanism for controlling the pressure circuit, two contact members for said contact mechanism, one of said members being associated with the coins passing through the machine and the other member being in driven connection with the movable element of the meter, clutch mechanism between the contact members adapted to allow slight relative movement between said members independently of the movable element, means for normally holding said contact members in electrical engagement to close the pressure circuit whereby the electromagnetic mechanism therein is controlled to open the current circuit, and means upon engagement of coins with the one contact member for causing disengagement of said members to open the pressure circuit whereby the electromagnetic mechanism is controlled to close the current circuit, both contact members being then driven upon movement of the movable element.

2. The combination with the movable element and pressure and current circuits in a meter, of prepayment mechanism for controlling said circuits, electromagnetic mechanism for the prepayment mechanism included in the pressure circuit for controlling the current circuit, contact mechanism for controlling the pressure circuit, two contact members for said contact mechanism, one of said members being associated with the coins passing through the machine and the other member being in driven connection with the movable element of the meter, clutch mechanism between the contact members adapted to allow slight relative movement between said members independently of the movable element, means for normally holding said contact members in electrical engagement to close the pressure circuit whereby the electromagnetic mechanism therein is controlled to open the current circuit, and means upon engagement of coins with the one contact member for causing disengagement of said members to open the pressure circuit whereby the electromagnetic mech-

anism is controlled to close the current circuit, both contact members being then driven upon movement of the movable element, said one contact member acting also as an escapement means for allowing passage of the coins through the device at a rate proportional to the energy to be measured by the meter, disengagement of coins from the one contact member allowing relative movement of the contact members to again close the pressure circuit whereby the electromagnetic mechanism causes opening of the series circuit.

3. The combination with the movable element and energizing circuits of a meter, of prepayment mechanism for controlling the circuits, there being a coin slot through which coins may pass, an escapement wheel projecting into said coin slot for engagement with the coins upon their passage therethrough, a contact member connected rigidly with said escapement wheel, a companion contact member connected with the movable element to be driven thereby upon actuation thereof, yielding spring clutch mechanism between the contact members disposed to normally hold the contact members in one relative position to render the circuits ineffective, means upon passage of coins through the mechanism in engagement with the escapement wheel for moving the contact member in another relative position to render the circuits effective whereby the movable element is actuated, said contact members and escapement wheel upon actuation of the movable element being then driven together to allow escapement of the coins at a rate proportional to the energy to be measured by the meter, said clutching mechanism upon release of the wheel from coins causing return of the contact members to their normal relative position to again render the circuits ineffective.

4. The combination with the movable element and energizing circuits of an electrical meter, of prepayment mechanism for controlling the circuits, an escapement wheel disposed in the path of coins to the mechanism, a contact member rigidly connected with the escapement wheel, a pivot shaft upon which said wheel and associate contact member are adapted to rotate, a companion contact member secured to the shaft, gearing mechanism connecting said shaft with the movable element, said first contact member being confined to rotate through a small arc with respect to the companion contact member, said contact members being associated with the meter circuits, yielding means tending to hold the contact members in one relative position to render the circuits ineffective when there are no coins in engagement with the escapement wheel, and means upon engagement of coins with the escapement wheel for causing the contacts to move against the

action of said yielding means to change their relative position to render the circuits effective whereby the meter may operate.

5. The combination with the movable element and energizing circuits of an electrical meter, of prepayment mechanism for controlling the circuits, an escapement wheel disposed in the path of coins to the mechanism, a contact member rigidly connected with the escapement wheel, a pivot shaft upon which said wheel and associate contact member are adapted to rotate, a companion contact member secured to the shaft, gearing mechanism connecting said shaft with the movable element, said first contact member being confined to rotate through a small arc with respect to the companion contact member, said contact members being associated with the meter circuits, yielding means tending to hold the contact members in one relative position to render the circuits ineffective when there are no coins in engagement with the escapement wheel, and means upon engagement of coins with the escapement wheel for causing the contacts to move against the action of said yielding means to change their relative position to render the circuits effective whereby the meter may operate, said contact members upon actuation of the movable element then being driven together at a rate to allow escapement of coins by the escapement wheel at a rate proportional to the energy to be delivered through the meter.

6. The combination with coin controlling mechanism, of other mechanism controlled thereby, electromagnetic controlling mechanism and circuits therefor, contact mechanism for controlling said circuits, two contact members for said contact mechanism, one of said contact members being associated with the coins traveling through the controlling mechanism, the other contact member being connected with the mechanism to be controlled, means for causing relative movement between the contact members when there are no coins in the mechanism whereby said contact members are in electrical connection to close the circuit for the electromagnetic controlling mechanism whereby said electromagnetic mechanism is actuated to prevent movement of the mechanism to be controlled, and means when there are coins in the controlling mechanism for causing relative movement of the contact members out of electrical engagement whereby the electromagnetic mechanism is actuated to allow movement of the mechanism to be controlled, said contact members when out of electrical connection being both driven by the mechanism to be controlled to allow escapement of coins through the controlling mechanism at a proper rate.

7. The combination with mechanism to be controlled, of a coin controlled device for controlling said mechanism, electro-

magnetic mechanism for said device connected with the mechanism to be controlled, circuits for said electromagnetic mechanism, contact mechanism for controlling said circuits, an escapement wheel adapted for engagement with coins passing through the device, a contact member for said contact mechanism rigidly connected with said escapement wheel, a companion contact member for said contact mechanism connected with the mechanism to be controlled, said contact members being normally in engagement to close the circuits through the electromagnetic mechanism whereby said electromagnetic mechanism is actuated to prevent movement of the mechanism to be controlled, means upon engagement of coins with the escapement wheel for causing relative movement of the contact members to be carried out of engagement with each other whereby the circuit through the electromagnetic mechanism is opened and the electromagnetic mechanism actuated to allow movement of the mechanism to be controlled, said contact mechanism and escapement wheel being thereupon driven through the connection thereof with the mechanism to be controlled, the rate of travel of the escapement wheel being adjusted to allow the proper rate of travel of the coins through the controlling device.

8. In a coin controlled device, the combination with an escapement wheel adapted for engagement with coins passing through the device, a contact member rigidly connected with said escapement wheel, a companion contact member, said contact members serving to control electrical circuits, driving means connected with said companion contact member, said contact members being relatively movable, means for limiting the range of said relative movement, yielding means tending normally to establish electrical engagement between said contact members, engagement of coins with the escapement wheel causing said yielding means to be overcome and the electrical connection between said contact members broken.

9. The combination with coin controlling mechanism, of driving means controlled thereby, an escapement wheel for engagement with coins passing through the controlling mechanism, a contact member rigidly connected with the escapement wheel, a companion contact member, said contact members serving to control electrical circuits connected with the driving means, said companion contact member being connected with said driving means to be driven thereby, means for allowing relative movement between the contact members, and yielding means serving to hold contact members in electrical engagement when there are no coins in the controlling mechanism whereby

the electrical circuits are controlled to prevent movement of the driving means, engagement of coins with the escapement wheel causing disconnection of the contact members against the action of said yielding means whereby the electrical circuits are controlled to allow movement of the driving means, said driving means then causing rotation of the contact members and escapement wheel, the driving connection being adjusted so that the escapement wheel will allow escape of coins at the desired rate, said contact members being maintained out of connection while there are coins in engagement with the escapement wheel, said yielding means causing reengagement thereof upon disengagement of coins from the escapement wheel whereby the electrical circuits are restored to prevent actuation of the controlled driving means.

10. In a coin controlled device for controlling driving mechanism, the combination with an escapement wheel adapted for engagement with the coins passing through the device, of a contact arm connected rigidly with the escapement wheel, a companion contact arm associated with said first contact arm and connected with the driving means to be driven thereby, said contact members serving to control electric mechanism connected with the driving means, there

being a slot in said companion contact arm in which the end of the first contact arm may play to allow limited relative rotation between said contact arms, said first contact arm when at one end of said slot being in electrical engagement with the companion contact arm, and spring means tending to hold the arms in such electrical position, said first arm being insulated from the companion arm when at the other end of the slot, engagement of coins with the contact wheel causing the first contact arm to be rotated out of electrical engagement with the second contact arm whereby the electrical mechanism is controlled to allow actuation of the driving means, said driving means then causing combined rotation of the contact arms and escapement wheel to control the escapement of coins through the machine, said contact arms upon disengagement of coins from the escapement wheel being returned to their normal position of electrical engagement, whereby the electrical mechanism is restored to prevent movement of the driving means.

In witness whereof, I hereunto subscribe my name this 27th day of Nov. A. D., 1905.

HENRY W. SAYLES.
